UNITED STATES PATENT OFFICE.

IRA R. WILLIAMS, OF PORTLAND, OREGON.

AUTOMATIC WINDOW-CATCH.

1,135,147.

Specification of Letters Patent. Patented Apr. 13, 1915.

Application filed July 20, 1914. Serial No. 852,029.

To all whom it may concern:

Be it known that I, IRA R. WILLIAMS, citizen of the United States, residing at Portland, in the county of Multnomah and State of Oregon, have invented certain new and useful Improvements in Automatic Window-Catches, of which the following is a specification.

This invention relates to automatic window catches and has as its primary object to provide a device of this character adapted to operatively engage the upper and lower sashes of a window to maintain each of said sashes in closed position, and which will also be adapted to operatively engage each of said sashes to maintain the sashes in various vertically adjusted positions within the window opening.

The invention has as a further object to provide a device of this character wherein the mechanism employed to engage each sash will operate to engage the sash independently of the other, and wherein each of said mechanisms may be simultaneously moved to inoperative position. And a still further object of the invention is to provide a device of this character which will be simple in construction and wherein the working parts thereof may be readily dismounted to permit of repair.

With these and other objects in view, my invention will be more fully described, illustrated in the accompanying drawings, and then specifically pointed out in the claims which are attached to and form a part of this application.

In the accompanying drawings:—Figure 1 is a front elevation showing my improved catch applied within a window casing, the window casing being shown partly broken away and certain portions thereof, being illustrated in section. Fig. 2 is a top plan view taken on the line 2—2 of Fig. 1, and illustrating the catch members moved to operative position. Fig. 3 is a horizontal sectional view particularly illustrating the manner in which the catch members are mounted, and Fig. 4 is a detail perspective view showing one of the links employed to operatively connect the catch members with the operating rod therefor.

Corresponding and like parts are referred to in the following description and indicated in all the views of the drawings, by the same reference characters.

For convenience, I have illustrated in

Fig. 1 of the drawings, my improved catch applied, and wherein the numeral 10 designates a window casing in which is slidably mounted, as will be readily understood, the upper and lower sashes 11 and 12.

More particularly, said catch includes a frame or supporting member 13 which is preferably formed from a strip of suitable sheet metal and is substantially rectangular as shown, one side member 14 of the frame being preferably detachably secured to the body portion thereof in any suitable manner, as by bolts 15. Extending between the side portions of the frame and in substantial parallel relation to the end portions thereof, is an intermediate supporting strip 16, which is detachably connected in any suitable manner, at its ends, with the side portions of the frame. Preferably, the supporting strip 16 is provided, at its ends, with tongues 17, which fit within suitable apertures formed in said side portions.

The frame 13 is positioned within one side portion of the window casing, as best shown in Fig. 1 of the drawings, to bear between the adjacent inner face of the side portion 18 of said casing and a contiguous face of the vertically arranged support 19, the said frame being arranged medially of and in substantial alignment with the overlapping portions of the upper and lower rails of the upper and lower sashes 11 and 12. Mounted upon said frame to operatively engage said sashes, are the laterally spaced and horizontally arranged catch members, each of which is indicated as a whole at 20. The said catch members each include a terminal bolt 21, which may be formed of suitable metal and which is preferably cylindrical throughout the greater portion of its length and is terminally enlarged at one end, to provide a head 22. The said bolts 21 are slidably mounted within suitable apertures formed in one end portion of the frame 13 with the heads thereof, confronting the inner face of said side portion, and screw threaded at one end, into each of said heads 22, is a connecting rod 23, the said rods, adjacent their opposite extremities being slidably mounted within suitable apertures formed in the supporting strip 16.

At their rear extremities, each of the rods 23 is bifurcated to provide a yoke 24, to each of which is pivotally connected at one end, by a suitable pin 25, a link 26.

Mounted for rotation upon the side mem-

bers of the frame 13 in the rear of the supporting strip 16, and extending in substantially parallel relation thereto, is an operating rod 27, said rod being received within 5 suitable apertures formed in said side members. Formed on the rod 27, adjacent one end thereof, is a collar 28, disposed to contact with the adjacent inner face of the side member 14 of the frame to thus maintain the 10 operating rod in position.

Extending radially from the operating rod 27 and arranged in substantial alinement with the links 26, are crank arms 29, each of 15 which is provided adjacent its free extremity, with a terminal pivot pin or arm 30 arranged in substantially parallel relation to the operating rod 27.

Adjacent their inner extremities, each of the links 26 is laterally enlarged as shown at 20 31 and formed in each of said laterally enlarged portions, is a longitudinally extending slot 32, said slots being adapted to receive the pivot pins of the crank arms 29. The bolts 21 are thus operatively connected 25 with the operating rod 27, and arranged to normally maintain said bolts projected to operatively engage the window sashes 11 and 12, as will be presently described, are helical springs 33, said springs being each arranged 30 to encircle one of the connecting rods 23, and being interposed between the head 22 of the adjacent bolt and the supporting strip 16. The bolts 21 are of such length as to project, at their free extremities, through 35 suitable apertures formed in the side portion 18 of the window casing and into the path of the upper and lower sashes 11 and 12, and formed in the adjacent edges of the side members of said sashes, are a series of longitudinally spaced and transversely extending 40 recesses 34, the recesses of each sash being adapted to receive the free end of the adjacent bolt 21. It will be noted that the bolts 21 will normally engage said sashes, and in 45 order to facilitate the moving of said bolts to inoperative position, I provide the operating rod 27, upon its outer free end, with a terminal knob 35, said knob being preferably screw threaded upon the operating rod, 50 so that it may be readily detached, it being understood that the operating rod 27, is of such length as to project through the adjacent outer face of the window casing 10, so that free access may be had to the knob 35.

55 From the above description, the operation of my improved catch will be readily understood. The bolts 21 being normally projected to engage the sash 11, as above described, to withdraw said bolts against the tension of the springs 33, the operating rod 27 is rotated by the knob 35, to cause the crank arms 29 to be turned rearwardly, when the pins 30 will move to engage within the adjacent extremities of the slots 32 of the 60 links 26, to thus move the links rearwardly, 65

which being each in turn operatively connected to the bolts, will withdraw said bolts to inoperative position, out of engagement with the sashes 11 and 12.

Particular attention is now called to the 70 fact that my improved catch is not only adapted to maintain the upper and lower sashes 11 and 12 in position to close the window opening, but is also adapted to hold each of said sashes in various adjusted positions within said window opening when 75 said sashes are moved to open the window. This is a decided feature of advantage of my invention, since certain types of conventional forms of catches as now in common 80 use, while being adapted to maintain the lower sash in various adjusted open positions, are not adapted to similarly engage the upper sash. For a like purpose, it is to be noted that, if desired, when the lower 85 sash is raised so that any one from the exterior of the window could reach the operating knob 35 to effect the release of the sashes, and consequently entirely open the window, the knob 35 may be removed, making it at least, very difficult, if not practically impossible, to turn the operating rod 27 to effect such result. It is also desired to direct attention to the fact that in the normal position of the operating rod 27 as 90 shown in Figs. 2 and 3 of the drawings, the catch members are capable of movement to operatively engage the sashes 11 and 12 independently of each other. Thus, after the operating rod 27 has been turned, to 100 withdraw the bolts 21, and the sashes 11 and 12 are moved to such position that neither of the bolts will coincide with one of the recesses 34, but will, upon the release of the operating rod, bear upon the adjacent 105 edges of the side members of the sashes, each of said bolts will drop into the next adjacent recess upon the movement of the contiguous sash, independently of the other, through the action of the springs 33, this 110 result being had through the provision of the slots 32 in which the pins 30 engage. It will be noted that in order to withdraw the bolts 21, the pins 30 must be moved to the outer extremities of said slots, and that 115 normally, said pins are disposed medially thereof, so that the links 26 will slide upon said pins independently of the operating rod 27, and consequently permit the bolts 21 to independently engage the upper and lower 120 sashes as above described.

125 Preferably, the outer side member 14 of the frame 13 is arranged flush with the inner edge of the window casing, as shown in Fig. 2 of the drawings, and it will be observed that by removing the side member 14, the working parts of the catch members may be entirely removed from the frame. Thus, the bolts 15 may be withdrawn to displace the member 14, and the supporting strip 16 130

and the operating rod 27, may then be removed, the bolts 21 being first withdrawn through the adjacent side member of the frame 13. This is also an important feature 5 of my invention, since it permits of ready access to the catch members, in case the catch does not operate properly, and also permits of ready repair in case of breakage.

It will therefore be seen that I provide a 10 very simple and efficient construction for the purpose set forth wherein the upper and lower sashes of a window may be maintained in closed position and may each be maintained in various adjusted open positions. It will further be seen that the catch members will normally automatically engage each of the window sashes, and that upon the release of the operating rod for 15 said catch members, that each thereof will 20 move to engage the adjacent sash independently of the other.

Having thus described my invention, what I claim and desire to secure by Letters Patent is:—

25 1. A device of the character described including a supporting frame, a supporting strip carried thereby, bolts slidably mounted upon the frame and supported by said strip, said bolts being adapted to engage a 30 window casing and being provided with heads forming shoulders arranged to limit the bolts in their movement upon the frame in one direction, an operating rod mounted for rotation upon the frame, crank arms 35 formed on said operating rod, links pivotally connected to said connecting rods, the

said links being slotted adjacent one extremity, pins arranged upon said crank arms and engaging in said slots, the links being mounted for sliding movement upon said 40 pins, and springs surrounding the connecting rods and interposed between the heads of the bolts and said supporting strip, said springs being disposed to normally maintain 45 the shoulders formed by the heads of the bolts in engagement with the adjacent portion of the supporting frame.

2. A device of the character described including a support, resiliently actuated bolts carried thereby and normally disposed to 50 engage a window sash, a rotatably mounted operating rod carried by the support, and connecting means operatively and slidably connected to said rod and having operative connection with the bolts. 55

3. A device of the character described including a supporting frame, bolts slidably mounted upon the frame and adapted to engage a window casing, an operating rod mounted for rotation upon the frame, links 60 having slidable connection with said rod and being operatively connected to said bolts, and resilient means engaging the bolts for normally maintaining the said bolts in engagement with the window casing. 65

In testimony whereof I affix my signature in presence of two witnesses.

IRA R. WILLIAMS. [L. S.]
